UNITED STATES PATENT OFFICE.

HENRY M. SHEER, OF QUINCY, ILLINOIS.

COOKER.

1,005,660.

Specification of Letters Patent. Patented Oct. 10, 1911.

Application filed November 13, 1909. Serial No. 527,908.

To all whom it may concern:

Be it known that I, HENRY M. SHEER, a citizen of the United States, residing at Quincy, in the county of Adams and State 5 of Illinois, have invented certain new and useful Improvements in Cookers, of which the following is a specification.

My invention relates to an improvement in sectional trucks for cookers, the object 10 being to provide means whereby additional cookers can be added at any time, and with this object in view, my present invention consists in a sectional base or truck capable of being enlarged or reduced in size to accommodate 15 two or more cookers, in connection with ovens held by these base or truck units or sections.

My invention further consists in certain novel features of construction and combinations of parts which will be hereinafter described and pointed out in the claims.

In the accompanying drawings:—Figure 1 is a horizontal section; Fig. 2 is a bottom plan view; Fig. 3 is an end elevation; and Fig. 4 is an enlarged detail showing an approved mode of connecting two sections or units.

The base or truck may consist of two or more units or sections and in the illustration 30 of my invention there are three of these, namely, the end sections or units 1 and 3, and the intermediate section 2. The end sections are preferably just alike, and comprise circular flanged rims upon which the 35 cookers 4, 4, are held and supported. On the lower side, ball-bearing or other forms of casters or rollers 5, 5, are secured to facilitate moving the sectional truck about on the floor. The intermediate sections or units, 40 whether there be more than one, are, in general outlines, the same as the end sections or units, but they differ slightly from the latter, in that they have two sets of fastening lugs, 6, 6, whereas the end sections or 45 units only have one set of fastening lugs, 7, 7, and in each of the sections, one lug of the pair preferably overlaps, and the other underlaps the lug of the next section to which it is secured, bolts 9, 9, being inserted 50 through bolt holes 10, 10, in these lugs, and having nuts 11, 11, thereon, whereby to removably secure the sections or units together. Each section or unit is composed mainly of a horizontal annular ring sur-

mounted at the outer edge by an annular up- 55 turned flange 14 whereby to form a seat for the article supported upon the section or unit of the base. Extensions 15—15 project from these flanges 14 adjacent to and throughout a portion of the length of the 60 lugs 6 and 7 and their ends are adapted to abut each other when the lugs are overlapped, thereby affording greater strength and rigidity to the base. While it is evident that either less or more than three of these 65 sections or units might be employed, and they might be fastened together in any approved manner, nevertheless, the invention sought to be covered is a sectional truck, or, in other words, a cooker capable of being enlarged or 70 reduced in size to suit the requirements of the user, the addition of each unit or section increasing the capacity of the truck to the extent of one whole oven or cooker. In this way, a simple truck for fireless cookers 75 is provided for domestic purposes capable of adjustments to the requirements of the user, it being so composed and assembled that its size may be altered without difficulty or skilled labor.

It is evident that more or less slight changes might be resorted to in the form and arrangement of the several parts described without departing from the spirit and scope of my invention, and hence, I do 85 not wish to limit myself to the exact construction set forth, but:—

Having fully described my invention, what I claim as new and desire to secure by Letters Patent is:—

1. A base comprising sections, said sections each adapted to support a cooker and having upturned flanges in position to have their ends abut, and each section provided with a horizontally disposed lug, the lugs of 95 the two adjacent sections overlapping, and fastening means connected with said lugs for detachably holding them together.

2. The combination with a truck composed of sections for supporting fireless 100 cookers, of annular flanges formed on the sections for retaining the cooker upon each section, lugs on the sections, the lug of one section adapted to overlap the ends of the other, and means for connecting the lugs together.

3. A base comprising sections for supporting fireless cookers, each section composed of

a horizontal annular ring, an annular flange formed on each ring for retaining the cooker thereon, extensions formed on the flanges, the ends of which are adapted to engage the 5 ends of the extensions of the adjacent sections, and means for connecting the sections together.

In testimony whereof I affix my signature, in the presence of two witnesses.

HENRY M. SHEER.
